(54) **DISTILLING, BOILER, & RECTIFYING
STILL**

(76) Inventor: **William Eaton**

the referred to in these Letters patent, and making part congeneric description in the words of the said William Bolton himself, of his improvements in the Water invented by Timothy Kirk, and in the dredging Sile patented to William Chamberlain.

These improvements, are in the form of the pipes which carry the liquor from the boiler, in full and so placing them as to communicate the heat to the water, gas, or air, or vapors, at the same time, upon the same fire. In the fitting a copper head to Timothy Kirk's boiler, converting it into a still, and in introducing this into the dredging still of Mr. Chamberlain, or any other still, a basket, or the perforated vessel is held contain grain or other substance from which the spirit or volatile extract is obtained.

the still
use of these improvements consists in forming the pipe communicating with
is, in a spiral manner, so as to expose the greatest surface of heat with
the being made such that tube is each such tube is
over still at different heights, so as to pass over a
through the tube. These tubes are placed
and in the most convenient places to be
convenient in the application of a head
or top of still, when the tube is so
as to be distilled over the still, yet it
improvement will be found that part of a
or not with head, or some other vessel, to
of the vapour into spirit or volatile extract
out which is applicable to stills of every description can
be a perforated tube within the body of the still, containing
substance which in the ordinary process of distillation
the still and render the product impure.
